[57] CLAIM

The ornamental design for a ski retention post for maintaining pairs of skis in pressure retention contact across a pair of roof mounted ski racks, as shown and described.

DESCRIPTION

FIG. 1 is a top, front and right side perspective view of a ski retention post for maintaining skis in pressure retention contact across a pair of roof mounted ski racks showing our new design;

FIG. 2 is a right side elevational view thereof, the left side being a mirror image of that shown;

FIG. 3 is a top plan view thereof;

FIG. 4 is a front elevational view thereof;

FIG. 5 is a rear elevational view thereof; and,

FIG. 6 is a bottom plan view thereof.
